Primary Examiner — Stacia Cadmus(74) *Attorney, Agent, or Firm* — Payam Moradian(57) **CLAIM**

I claim the ornamental design for an automobile wheel, as shown and described.

DESCRIPTION

FIG. 1 is a front elevational view of an automobile wheel; and,

FIG. 2 is a perspective view thereof.

The broken line showing of the rear of the rim is included for the purpose of illustrating environmental subject matter and forms no part of the claimed design.
